UNITED STATES PATENT OFFICE

GEORGE WILLIAM EVANS, OF WILKES-BARRE, PENNSYLVANIA

MOUNTING FOR FLYER BLOCKS

Application filed November 18, 1929. Serial No. 408,078.

This invention relates to improvements in flyers for spinning machines, and has in view to provide a novel combination of features in the construction and mounting of a flyer block 5 intended to provide an adequate remedy correcting certain defects inherent to flyer blocks as at present generally constructed and used.

According to present practice flyer blocks usually are retained on the bobbin spindles 10 by means of buttons frictionally engaged with the bobbin spindles, but due to wear on the buttons and bobbin spindles after long use, and to the practical impossibility of constructing the buttons and the bobbin spin- 15 dles with sufficient accuracy so that each button will fit in the same manner as another on each bobbin spindle, it frequently happens that a flyer block will not be allowed sufficient play or will be allowed too much play, 20 by its retaining button and by the position of the bobbin on the spindle to operate properly. Moreover, the retaining buttons may, and quite frequently do, fly off from the bobbin spindles, releasing the flyer blocks 25 which themselves quite frequently fly off, causing breakage of the thread and loss in time and material in effecting the necessary repairs.

The present invention, therefore, has in 30 view the provision of a flyer block and means for mounting same in operative relation to a bobbin and a bobbin spindle, whereby the aforementioned disadvantages at present generally experienced may effectively be 35 overcome, the present flyer block being positively retained in assembly with the bobbin when the latter is mounted on a spindle and, irrespective of wear on the spindle or the bobbin, having at all times substantially the 40 same amount of looseness or play longitudinally with respect to the spindle, so that an even tension on the thread is maintained. Thus, the present flyer block construction and mounting is designed to eliminate machine 45 stoppages due to loss of flyer blocks and to thread breakages resulting from uneven tensioning of same; to reduce flyer block costs; to enable increased production by the em- 50 ployment of minimum labor, due to the pres- ent flyer blocks requiring only minimum at-

tention, and to effect a saving in material by reducing thread breakages.

With the additional purpose of providing a relatively simple, inexpensive flyer block and simple, inexpensive means, easily 55 manipulatable for detachably, positively mounting same in operative relation to a bobbin and its spindle and against accidental loss therefrom, the invention consists in the novel features of construction, combination 60 and arrangement of parts as will be hereinafter more fully described, illustrated in the accompanying drawings and defined in the appended claims.

In the drawings, wherein like characters 65 of reference denote corresponding parts in the different views:—

Fig. 1 is a view in side elevation illustrating the present flyer block mounted in operative relation to a bobbin and a bobbin spindle. 70

Fig. 2 is a top plan view of the structure shown in Fig. 1.

Fig. 3 is an enlarged sectional view on the line 3—3 of Fig. 1 showing in detail the manner of connecting the flyer block with the bobbin. 75

Fig. 4 is a view similar to Fig. 3 showing the manner of engaging and disengaging the 80 flyer block with and from the bobbin; and

Fig. 5 is a detail perspective view of the 85 flyer block mounting tube.

Referring to the drawings in detail, A designates a bobbin, B a spindle on which 85 said bobbin is adapted to be engaged in the usual manner for rotation thereby, and C the present flyer block.

In accordance with the invention, the usual screw retained flange 10 at the upper end of the bobbin A is provided with a relatively 90 large central hole in which is secured, by a forced fit or in other suitable manner, a sleeve 11 provided at its outer end with an inturned flange 12. Thus, a recess 13 is provided between the flange 12 and the end of the bobbin, and within this recess is disposed a coil spring 14 which holds a ring 15, movable longitudinally within the sleeve 11, normally 95 in engagement with the inner face of the inturned flange 12 of said sleeve. 100

The present flyer block C carries, in any suitable manner, the usual arms 16 of wire or other material, having the loops or eyes 17 at their ends through which the strands from the bobbin are adapted to be threaded for twisting or spinning in the usual well known manner. This flyer block, in accordance with the present invention, is mounted loosely on a tube 18 for free rotation with respect thereto, the inner end of said tube having opposite and outwardly extending lateral flanges 19, 19 limiting movement of the block along said tube in one direction when the tube is disengaged from the bobbin, and a contractible ring or band 20 being engaged in an annular groove formed in said tube near its outer end to limit outward movement of the block and retain same in assembly with said tube.

As is apparent from the drawings, the flanges 19 of the tube 18 are adapted to be engaged between the inturned flange 12 of the sleeve 11 and the ring 15, whereby the flyer block is maintained effectively in assembly with the bobbin A, for quick and easy detachment therefrom; when the bobbin is removed from the spindle B. In this respect it will be noted that the diameter of the hole formed by the inturned flange 12 of the sleeve 11 is less than the length from end to end of the flanges 19 of the tube 18. Consequently, to assemble the tube 18 with the bobbin, it is necessary to tilt the tube with respect to the bobbin as illustrated in Fig. 4, engage one of the flanges 19 against the ring 15, press inwardly against said ring and at the same time shift the tube laterally to engage said flange 19 beneath the flange 12, and then rock the tube into axial alignment with the bobbin and shift same laterally in an opposite direction to engage the other flange 19 beneath the flange 12. This is a simple operation and may be readily accomplished, whereafter the spring 14 by its pressure against the ring 15 forces the latter against the inner flat faces of the flanges 19 and thus maintains the outer faces of the latter engaged against the flange 12 and the tube with the flyer block thereon in assembly with the bobbin against disengagement therefrom by any movement except a reversal of the combination of movements just recited.

With the tube 18 assembled with the bobbin in the manner stated, it is apparent that when the bobbin is engaged over the spindle B, as shown in Figs. 1, 2 and 3, the spindle passing upwardly through the tube 18 will maintain same centered with respect to the bobbin so that any tilting movement of the tube essential to effect its disengagement from the bobbin is positively prevented. It is apparent therefore that by reason of the present construction the flyer block cannot accidentally fly off during use, nor can it accidentally be disengaged from the bobbin

when the latter is removed from the spindle, and furthermore, as is manifest, the position of the bobbin along the spindle is ineffective to alter the looseness or play of the flyer block or to vary the tension imposed by the same on the thread, since the distance between the outer face of the flange 12 and the stop remains constant irrespective of wear which may permit the bobbin to be moved a greater or less distance onto the spindle B.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. In combination with a bobbin having a recess and an annular flange extending into said recess, a tube provided with lateral flanges engageable behind the flange of said bobbin, spring means within said recess pressing the flanges of said tube against said bobbin flange, and a flyer block carried by said tube.

2. In combination with a bobbin having an opening surrounded by a flange, a tube having oppositely directed lateral flanges of a total length from end to end greater than the diameter of said opening, insertable through the latter and engageable behind said first mentioned flange by tilting movement of said tube with respect to said bobbin, and a flyer block rotatably mounted on said tube.

3. A flyer device comprising the combination with the bobbin having a flange projecting inwardly therefrom, of a tubular member having a laterally projecting flange at one end for engaging beneath the flange of the bobbin, said tubular member also having a shank portion of uniform diameter throughout, a flyer block mounted for free rotation on the said shank of the tubular member, and locking means on the end of the shank spaced from the top of the flyer block whereby the said flyer block may have a movement longitudinally of the shank as well as rotatably thereon.

4. In a flyer twisting frame, the combination with the bobbin and flyer, of a flange projecting inwardly from the bobbin and a companion flange projecting outwardly from the flyer, the two flanges being held in given position by means of the spindle, and said flyer including a tubular shank portion extending away from said companion flange, a flyer block mounted on said tubular shank portion, and a locking ring detachably engaging the end of the tubular shank opposite said companion flange.

5. In combination with a bobbin having an opening surrounded by a flange, a flyer

block device including a tubular portion having oppositely directed offset portions of a total length from end to end greater than the diameter of said opening and insertable 5 through the latter to be engaged behind said flange by a tilting movement of said flyer device with respect to said bobbin.

6. The combination with a bobbin and the spindle passing through an opening in the 10 bobbin, said bobbin having a recess surrounding said opening, a flange surrounding the recess and providing a flyer block receiving opening, a flyer block device including a tubular portion provided at its lower end 15 with opposite projections of a total length from end to end greater than the diameter of said opening formed by the flange, whereby the flyer block may be inserted behind the said flange by a tilting movement with respect to the bobbin, and the spindle will center and lock the flyer block within said flange.

In testimony whereof I hereunto affix my signature.
